VIDEOTELEPHONE TRANSCEIVER CONTROL UNIT

Henry Dreyfuss, South Pasadena, Calif., and Rembert R. Stokes, Middleton, N.J., assignors to Bell Telephone Laboratories, Incorporated, Murray Hill, N.J., a corporation of New York

Original design application Nov. 24, 1967, Ser. No. 9,549, now Patent No. 215,159, dated Sept. 9, 1969. Divided and this application Oct. 3, 1968, Ser. No. 15,936

Term of patent 14 years

Int. Cl. D14—03

U.S. Cl. D26—14

FIG. 1

FIG. 2

FIG. 3

FIG. 4

FIG. 5

FIG. 1 is a right front perspective view of a videotelephone transceiver control unit showing our new design;

FIG. 2 is a lower right front perspective view of the videotelephone transceiver control unit shown in FIG. 1;

FIG. 3 is a left rear perspective view of the videotelephone transceiver control unit shown in FIG. 1;

FIG. 4 is a left front perspective view of a videotelephone transceiver control unit showing our new design;

FIG. 5 is a right front perspective view of the videotelephone transceiver control unit shown in FIG. 4.

This is a division of design application Ser. No. D. 9,549, filed Nov. 24, 1967, and now Pat. Ser. No. D. 215,159.

We claim:

The design for a videotelephone transceiver control unit, substantially as shown and described.
